UNITED STATES PATENT OFFICE.

RUDOLPH H. BECK, OF PHILADELPHIA, PENNSYLVANIA.

DESIGN FOR A BRACKET OR SUPPORT FOR CURTAIN-POLE HOLDERS.

SPECIFICATION forming part of Design No. 34,082, dated February 12, 1901.

Application filed January 14, 1901. Serial No. 43,290. Term of patent 14 years.

To all whom it may concern:

Be it known that I, RUDOLPH H. BECK, a citizen of the United States, residing at the city of Philadelphia, in the county of Philadelphia and State of Pennsylvania, have invented and produced a new and original Design for a Bracket or Support for a Curtain-Pole Holder, of which the following is a specification, reference being had to the accompanying drawings, forming part hereof, in which—

Figure 1 is a side elevational view of a bracket or support for a curtain-pole holder, showing my design. Fig. 2 is a top edge view of the same, and Fig. 3 is a front edge or elevational view of the bracket or support of Fig. 1.

As illustrated, the leading or material feature of my design consists of the configuration or shape of the bracket or support for the curtain-pole holder, which viewed in side and front elevations, as illustrated in Figs. 1 and 3, comprises an oblong support A, provided with apertures or openings a and a', near re-

spective outer rounded ends thereof. The support A is made to curve into an integral horizontal and vertical arm B, provided with an annular stop b, at or near the upper rounded end of the same. The merging of the support into the horizontal portion of the arm B is at a point a greater distance from one portion of the support than from the other portion thereof. The horizontal and vertical arm B in outline is rounded at b', as illustrated in Fig. 1.

Having thus described my invention, what I claim as new, and desire to secure by Letters Patent, is—

The design for a bracket or support for a curtain-pole holder, substantially as shown and described.

In witness whereof I have hereunto set my signature in the presence of two subscribing witnesses.

RUDOLPH H. BECK.

Witnesses:

J. WALTER DOUGLASS,
THOMAS M. SMITH.
